UNITED STATES PATENT OFFICE.

WILLIAM T. SMITH, OF PHILADELPHIA, PENNSYLVANIA.

DESIGN FOR WOVEN FABRIC.

SPECIFICATION forming part of Design No. 33,897, dated January 8, 1901.

Application filed November 5, 1900. Serial No. 35,579. Term of patent 7 years.

To all whom it may concern:

Be it known that I, WILLIAM T. SMITH, a citizen of the United States, residing in Philadelphia, Pennsylvania, have invented and produced a new and original Design for Woven Fabric, of which the following is a specification.

My design for a woven fabric is fully shown in the accompanying drawings, which represent it in the form of a curtain.

Figure 1 is a front view of the curtain as it appears when hung over a pole, and Fig. 2 an edge view of the same.

As shown, the design is represented as it appears when in use as a curtain, being hung upon a pole, so as to present a long depending rear portion and a short depending front portion which overlaps the upper part of said depending rear portion. That portion of the design which is thus hidden is, however, simply a repetition of a part of the design which is shown.

The design comprises a body 2 and end borders 3 and 4. The body 2 consists of plain

bands 5, alternating with bands 6, having 25 ornamentation mainly of a floral character, and bands 7, having ornamentation mainly of a scroll pattern. The end border 3 comprises a plain body 5 and a band 8, the pattern of which is similar to that of the band 30 6, but on a larger scale. The end border 4 comprises a plain band 5 and a wide band 9, having both floral and scroll ornamentation.

The design is applicable to table-covers, drapery, and hangings generally.

Having thus described my invention, I claim and desire to secure by Letters Patent—

The design for a woven fabric, substantially as described and as shown in the accompanying drawing.

In testimony whereof I have signed my name to this specification in the presence of two subscribing witnesses.

WILLIAM T. SMITH.
